UNITED STATES PATENT OFFICE

2,005,851

VALVE SEAT GRINDER

Frans O. Albertson, Sioux City, Iowa, assignor to Albertson & Company, Inc., Sioux City, Iowa, a corporation of Iowa.

Application July 19, 1934, Serial No. 735,932.

8 Claims. (Cl. 51—241)

The present invention relates to valve seat grinding machines for the forming, reconstruction or repair of valve seats of internal combustion engines, and is particularly concerned with an improved angular attachment for grinding machines of the type covered by my prior application Serial No. 711,848 filed February 19, 1934 entitled Valve seat grinding machines.

Valve grinding machines of the prior art may be classified into machines of the full contact type in which the stone is in contact with the working surface to be ground throughout the entire periphery of the stone, and single contact machines in which the stone is so tilted that it contacts only one side of the valve; or the stone may be arranged eccentrically with respect to the axis of revolution.

The devices of the prior art have, however, been very complicated, requiring either a complicated mechanism for rotating and revolving the stone, or requiring a ball bearing tool holder for supporting the stone, and the devices of the prior art have not been able to grind the valves with a suitable finish.

The difficulty with the full seat contact grinding wheels of the prior art was that this resulted in clogging or loading of the wheel with the cuttings or material ground from the seat, and this caused a change in the contour of the stone and resulted in the grooving of the valve seat. All the devices of the prior art were also very expensive on account of the complicated mechanism required and on account of the apparent necessity for using anti-friction bearings, and such devices could not be brought within the means of the ordinary garage owners, who could not afford expensive mechanism and make a profit on the work to be done.

One of the objects of the present invention is the provision of an improved apparatus for reconstructing or grinding valve seats of very hard material, such as stellite, tungsten steel or other hardened alloys and which apparatus is peculiarly adapted to be utilized on the valves which are disposed in relatively inaccessible positions, such as the valves of the last cylinder which may be underneath the dash.

Another object of the invention is the provision of an angular attachment for valve seat grinders of the class described which is adapted to be secured to any kind of a motor driver to adapt the motor driver to the operation of a valve seat grinder of the type covered by my prior application.

Another object of the invention is the provi-

sion of an improved grinding tool of the full seat contact type which is adapted to eliminate the clogging and loading of the grinding wheel or the grooving of the seat, and to provide a grinding tool which is self-cleaning.

Another object of the invention is the provision of an improved grinding wheel adapted to disperse the cuttings continuously and to prevent loading of the wheel or filling with the cuttings of the interstices between the abrasive particles of the wheel at the surface, the cuttings being dispersed by current of air and centrifugal force, at the periphery of the wheel when the wheel is lifted periodically from the seat.

Another object of the invention is the provision of an improved method and apparatus which is adapted to disperse the cuttings by means of a vibratory movement of the stone either in a vertical direction on the pilot or angularly in a lateral direction by means of the flexibility of the pilot, so as to prevent loading of the wheel and grooving of the seat and to produce a finished surface on the valve.

Another object of the invention is the provision of an improved tool assembly, including a motor driver and a universal connection between the motor driver and the grinding wheel, including means for eliminating detrimental shocks on the grinding wheel, but adapted to produce a dual action of grinding and dispersion of the cuttings by means of a single grinding wheel mounted for full contact with the seat.

Other objects and advantages of the invention will be apparent from the following description and from the accompanying drawings, in which similar characters of reference indicate similar parts throughout the several views.

Referring to the drawings, of which there are two sheets, Fig. 1 is a side elevational view of a valve seat grinding apparatus constructed according to the present invention and including the improved angular attachment which facilitates the use of a grinder on valves underneath the dash.

Fig. 2 is a vertical sectional view of the valve seat grinding wheel tool holder and angular attachment showing a portion of the driver in elevation.

Fig. 3 is an enlarged fragmentary sectional view showing the driving connection between the drive shaft of the angular attachment and the tool holder.

Fig. 4 is a sectional view taken through the hub which surrounds the driving shaft of the motor driver, on the plane of the line 4—4 of

Fig. 1 looking in the direction of the arrows;

Fig. 5 is an enlarged fragmentary elevational view of the bevel gears utilized in the angular driving attachment, also showing the resilient mounting for the drive shaft of the attachment, and

Fig. 6 is a front elevational view of the spring utilized for resiliently mounting the drive shaft of the angular attachment.

10 Referring to Fig. 1, the complete assembly of the present grinding apparatus preferably includes the motor driver 20, a tool holder 21, an angular driving attachment 19, a grinding wheel 22, and a pilot stem 23.

15 The apparatus is illustrated in connection with a valve seat consisting of a hardened metal ring 24, which has been fixedly secured in the block 25 of an internal combustion engine having a valve seat guide 26.

20 The pilot 23 is preferably of the type having a lower cylindrical part 27 which fits the substantially cylindrical part of the valve stem guide 26 very closely, within one thousandth of an inch, for the purpose of centering the pilot 23 25 in the guide and locating it axially of the guide.

25 The pilot is also preferably provided with a very gradually tapered portion 28 which extends down into the upper part of the valve stem guide 26 and may be fixedly wedged in the guide 30 by merely shoving the pilot downward. The taper is preferably about twenty-three thousandths of an inch per foot, and constitutes the sole means of securing, but any suitable taper 35 may be used which will effect the wedging action and secure the pilot.

Another type of pilot which may be used is the expanding pilot shown in my prior Patent No. 1,902,207, issued March 21, 1933.

30 The motor driver 20 is described in detail in my prior application Serial No. 711,848, and preferably comprises an electric motor of the series wound type provided with suitable speed reduction gearing and having a downwardly projecting drive shaft for driving the tool holder 21.

45 The present grinder assembly is particularly adapted to be used in grinding valves when the engine block is supported by the chassis, by the angular attachment 19, which enables the operator to reach inaccessible valves which may 50 be underneath the dash 18 or made inaccessible by other parts of the automobile frame or mechanism.

55 In the prior application described the motor driver is provided with a shaft resiliently mounted for axial movement in order to permit vibratory movement of the driver and to support by means of springs or other resilient devices the weight of the motor.

60 In the present case, the drive shaft of the motor does not engage the tool holder, but it engages in a socket in the angular attachment, and therefore it is not essential that the motor driver be provided with a resiliently mounted and axially movable drive shaft when the angular attachment is used, since the angular attachment has its drive shaft so mounted.

65 The motor driver 20 is provided with a housing having at its lower end a substantially cylindrical portion 29 surrounding the motor drive shaft 30, which is provided with a non-circular (hexagonal) end 31.

70 The angular attachment 19 is provided with a substantially cylindrical socket 32 fitting about the cylindrical portion 29 of the motor driver 20, and the housing 33 of the angular attach-

ment is provided with laterally projecting lugs 34, 35 spaced from each other at 36 and adapted to be drawn together by a screw bolt 37 which passes through a cylindrical bore 38 in the lug 35 and is threaded into a threaded bore 39 in the lug 34.

75 When the lugs 34, 35 are in spaced relation to each other at the point 36, the cylindrical socket 32 of the attachment housing 33 fits about the cylindrical portion 29 of the driver 20, and therefore it may be clamped in place by drawing the lugs 34, 35 together with the screw bolt 37.

80 Socket 32 is preferably provided with an angular shoulder 40 which engages the end of the cylindrical portion 29 of a motor housing 29, thereby determining the final assembled position of these two parts.

85 The attachment housing 33 preferably comprises a tubular metal member having a pair of cylindrical portions 41, 42, which are hollow and communicate with each other, the axes of the cylindrical portions 41, 42 being arranged at an obtuse angle to each other, such as, for example, the angle shown in Figs. 1 and 2. This causes the motor driver 20 to project upwardly and laterally with respect to the tool holder 21, and, when the drive shaft of the angular attachment is engaged with the tool holder 21, enables the motor driver to be used without interference with the over-hanging dash 18 of the automotive vehicle.

90 The housing portion 41 of the angular attachment is provided with a bore 43 terminating at the annular shoulder 44 for receiving and seating the outer race 45 of the anti-friction bearing, 95 which also includes the ball bearings 46 and the inner race 47. Each of these races preferably has the partially circular ball groove for receiving the balls 46, and the inner race is preferably turned down at 48 to receive the inwardly projecting sheet metal seal 49, which is carried by the outer race by being secured in the groove 50 formed by spinning over the top of the outer race 45.

95 The anti-friction bearing 45, 46, 47 is secured in counterbore 43 by means of a tubular threaded member 51 which is threaded into the larger bore 52 to engage the outer race 45 and clamp it against the annular seat 44. Tubular threaded member 51 may be provided with an inwardly projecting flange 53 and with an aperture 54 for passing the driven shaft 55. The driven shaft 55 comprises a stub shaft having a reduced threaded portion 56 upon which is threaded the special pinion 57. The stub shaft 55 is also provided with an annular shoulder 58 and a larger cylindrical portion 59 fitting within the cylindrical bore of the inner race 47.

100 For the purpose of providing a better alignment, the shaft 55 is reduced in size at 60 and is provided with an annular shoulder 61 which engages the upper end of the inner race 47. The enlarged upper cylindrical portion 62 of the drive shaft 55 is provided with a non-circular (hexagonal) socket 63 adapted to fit the complementary hexagonal end 31 of the drive shaft 30 of the motor driver 20.

105 The driven shaft 55 may be fixedly secured by the clamping action of the special pinion 57, which has a threaded bore 64, and the pinion 70 clamps the inner race 47 between the pinion and annular shoulder 61. Driven shaft 55 is thus rotatably mounted by means of the anti-friction bearing 45—47 in proper position in the housing portion 41 to be engaged and driven by the drive 75.

shaft 30 of the motor driver 20 when the angular attachment 19 is clamped on the hub 29 of motor driver 20. In order to provide a better seat for the outer race 45 a steel washer 65 may be interposed between the outer race 45 and the annular shoulder 44.

The special pinion 57 might be termed a bevel gear, as it performs the function of a bevel gear meshed with another special pinion 66 carried by the drive shaft 67. These pinions are similar in formation and they are each provided with a substantially flat circular body 68 having laterally and axially projecting teeth 69. The tooth spaces 70 are deep enough so that axial movement may be permitted between the pinion 66 and housing portion 42, thus permitting the resilient mounting of the drive shaft 67, and the width of the tooth spaces 70 between the teeth 69 is also adapted to permit movement of the teeth of one pinion into the tooth spaces 70 between the teeth of the other pinion so as to effect continuous engagement but permit axial movement of the drive shaft 67.

The housing portion 42 is provided with a counterbore 71 terminating in an annular shoulder 72 against which is seated a steel washer 73. The steel washer 73 provides a seat for a resilient spring washer 74, which is shown in perspective in Fig. 6. This spring washer 74 comprises a flat annular metal member having a plurality of peripherally extending tongues 75 located about the bore 76 of the spring washer 74 and bent downwardly to engage a second steel washer 77. Three or more of the resilient spring tongues 75 are preferred in order to provide at least three point resilient support for maintaining the resilient projection of the shaft 67 from the housing 42.

The outer race 78 of the anti-friction bearing, which comprises the races 78, balls 79, 80 and inner race 81, is provided with an outer cylindrical surface slidably engaging the counterbore 71 so that the entire anti-friction bearing may slide axially in the bore 71.

The races 78, 81 are provided with the usual partially circular grooves for receiving the steel balls 79, 80, and the balls may be provided with the usual cages for holding them in predetermined position spaced with respect to each other peripherally of the races.

The housing portion 42 is provided with an enlarged counterbore 82, which is threaded to receive the threaded member 83, which has an inwardly extending flange 84 surrounding the enlarged bore 85, which passes the end of the drive shaft 67. The flat end of the threaded member 83 engages the end of the outer race 78 and acts as a stop to limit outward sliding movement of the race 78, the threaded member 83 being driven home in its threaded bore 82.

The drive shaft 67 is preferably provided with a non-circular (hexagonal) end portion 86 and a tapered frusto-conical portion 87 for engaging an oil seal. The threaded member 83 provides a housing for an oil seal, which may consist of a hat leather having an outwardly extending radial flange 88 and a cylindrical flange 89. The cylindrical flange 89 engages the tapered part 87 of shaft 67 and may be held in engagement with that part by an endless helical garter spring 90, which continuously draws the cylindrical flange 89 of leather against the smooth metal part 67 and prevents egress of lubricant at this point.

The radially extending flange 88 may be clamped against the flange 84 by means of a metal

washer 91, which in turn is engaged by the tubular spring housing 92. The tubular spring housing 92 has an inwardly extending radial flange 93, which engages the end of the outer race 78 and holds the spring 90 in proper position.

The drive shaft 67 also has a reduced cylindrical portion 94 which fits in the cylindrical bore of the inner race 81, and the end of the inner race 81 engages the annular shoulder 95. At its upper end the drive shaft is provided with a reduced threaded portion 96, upon which is mounted a suitable spacing member 97, and the inner race 81 is clamped between annular shoulder 95 and spacing member 97 by the special pinion 66, which has a threaded bore 98.

The inner race 81 is thus fixedly secured to the drive shaft 67 and adapted to move with it both in a rotary direction and an axial direction, while the outer race 78 is adapted to slide in an axial direction in the counterbore 71 against the compression of the spring 74.

The non-circular end 86 or driving knuckle on shaft 67 is preferably provided with a flat end 99, which is chamfered as at 100 for the purpose of removing the sharp edges which would otherwise wear, so that the physical characteristics of the end of the driving knuckle will remain the same.

The driving knuckle 86 is preferably made of special steel, and its action on the tool holder 30 will be described in detail hereinafter. The motor driver 20 preferably operates at a speed within the range of 13,000 R. P. M., which is considerably in excess of the speeds previously used by the drivers of the prior art, and the mechanism 35 is capable of operation at this high speed without the necessity for anti-friction bearings in the tool holder on account of the fact that there is no bearing load on the bearings of the tool holder except that which is involved by its guiding function.

The tool holder 21 preferably comprises a substantially cylindrical housing sleeve 101, which may serve as a handle, and which may be constructed of a fiber tube, phenolic condensation 45 compound, or other suitable material.

The housing 101 is supported by means of a supporting body or sleeve 102 of substantially cylindrical outer form and provided with the radially outwardly extending flange 103 at its 50 lower end adapted to be located flush with the outer surface of the housing 101.

Flange 103 is provided with an annular shoulder 104 adapted to receive the sleeve or housing 21, and the supporting sleeve 102 is provided with a 55 downwardly extending tubular portion 105, which is externally threaded for the purpose of receiving the threaded hub 106 of the grinding wheel.

The grinding wheel 22 comprises a suitable grinding stone of carborundum, emery, or other suitable material, which is secured to the tubular hub 106 by means of cement 107. On its upper surface the grinding stone 22 has a cardboard annulus or washer 108 cemented thereto, bearing the data regarding the size and angularity of the stone. The upper surface 109 of the grinding stone is flat, and the periphery 110 is substantially cylindrical. The bottom 111 is preferably flat, while the working surface 112 is accurately 70 frusto-conical in the case of valves for internal combustion engines.

The threads 75 on the hub 106 and tubular portion 105 are, of course, opposite in direction to the rotation of these parts, so that the wheel will 75

be driven home on its threaded support by the action of the driver.

The supporting sleeve 102 is provided with a cylindrical bore 113 extending throughout the major portion of the sleeve and with an enlarged counterbore 114 at the top. The counterbore 114 is threaded at its upper end 115 for receiving the end of plug 116, which has a reduced threaded end 117 threaded into the bore 115.

End plug 116 has an outwardly extending annular shoulder 118 which engages the end of the sleeve 102 when it is threaded home therein, and it is also preferably provided with a cylindrical surface 119 and the annular shoulder 120, the former being received in the housing 101, and the latter abutting against the end of the housing 101 for supporting the upper end of the housing 101 on the sleeve, 101, 102.

Pins 121 may be driven through the housing 101 into the bores 122 in the reduced portion 117 of plug 116 firmly to secure all of these parts together and prevent the threaded parts from coming loose.

The end plug 116 is provided with a bore 123 extending through it, and the bore 123 emerges into an enlarged recess or counterbore 124. The intervening surface of the plug is frusto-conical at 125 to provide a suitable clearance between the central part of a spring washer 126 and the parts of the end plug 116.

The spring washer is illustrated in greater detail in Fig. 3 and comprises a resilient tapered steel member 126 circular in plan and preferably provided with a centrally located aperture 127. The spring washer is preferably provided with a plurality of radially extending rib formations 128, which in this case are located on two diameters at right angles to each other, for the purpose of further stiffening the spring, but in some embodiments of the invention the spring might be made of sufficient stiffness without the ribs 128.

The ribs 128 preferably extend downward when the spring washer 126 is assembled with the tool holder 21 so as to increase the bearing surface against which the end of the driving knuckle 86 engages over the surface which it would engage if the ribs projected upward. The spring washer 126 rests against an annular shoulder 129 at the base of the counterbore 124 and is clamped in place by a threaded member 130, the end of which engages the upper surface of the spring adjacent its periphery.

The threaded member 130 has its periphery threaded to be received in the threaded bore 124, and it also has its threads extending in such a direction that it will be driven home by the driving action of the motor driver. The threaded member 130 is provided with a centrally located aperture 131, which is preferably non-circular in form and complementary to the shape of the driving knuckle 86. The aperture is slightly larger than the driving knuckle 86 so as to permit the driving knuckle to tilt in the non-circular or hexagonal aperture 131, as shown in Fig. 3.

The upper end 132 of the pilot 23 is cylindrical in form and preferably made of hardened steel, and the bore 113 of the sleeve is provided with a bearing sleeve 133 having an accurate cylindrical bore 134. The bearing sleeve 133 is also preferably made of hardened steel. As these parts have very little bearing pressure on each other, they may be constructed of hardened steel and made to fit accurately by lapping them in and they retain their fit for a long period of time and do not pick up the particles of grindings or

grains from the grinding wheel as do the softer metals used in the prior art. Thus, the guiding surfaces of the tool holder and pilot do not wear materially and may be kept accurate for a long period of time.

With a slight amount of lubricant on these two hard contacting surfaces the device may be driven at very high speeds, such as, for example, 13,000 R. P. M., without appreciable wear, whereas the devices of the prior art which were driven slower required the use of anti-friction bearings.

Referring, now, to Fig. 2, it will be evident that the drive shaft 67 may be moved inward and outward with respect to the motor 20 by virtue of the sliding arrangement of the bearings and the resilient action of the spring 74 which urges the shaft outward. This spring action eliminates shocks on the grinding wheel which might otherwise be caused by the unsprung weight of the motor, and the spring 126 in the tool holder has a similar action in preventing such heavy shock to the grinding wheel that the grinding wheel would break.

Referring to Fig. 1, this is a side elevational view of the assembly with the driver in the position which it assumes when the operator begins his operations. While the driver is operating at high speed the operator sways the handle 132 back and forth through a relatively small arc, moving the driving motor angularly with respect to its driving knuckle 86. This results in a different action on the driving wheel 22 and effects a dispersion of the cuttings and constant cleaning of the grinding wheel.

Referring to Fig. 3, it will be observed that the non-circular or hexagonal end of the driving knuckle is there shown at an angle with the end plug 116, or at an angle to the axis of the pilot 23 and tool holder 21. As the hexagonal part 86 rotates there is an axial movement of this hexagonal part, due to the distance between the spring 126 and the successive corners 133, 134, 135, 136 of the hexagonal part.

In other words, at the instant shown, the corner 136 of the driving knuckle 86 is in engagement with the spring 126, but as the corner 136 rotates downward toward the position where it will engage the spring 126 there is an axial movement of the drive shaft downward which is equal to the distance X shown in Fig. 3.

Thus, the use of a non-circular driving member disposed at an angle causes the drive shaft to give a number of downward impulses to the tool holder, the shock of which is, however, partially absorbed by the spring 126, and the shock of the motor weight is not transmitted to the tool holder on account of the fact that the motor is spring supported by means of the spring 74.

This vertical impulse action of the drive shaft on the tool holder produces variations in pressure on the grinding wheel 22 as it grinds the seat 24. Furthermore, the pilot stem 23 is a relatively slender and resilient metal member, and the tilt of the drive shaft 48 and driving knuckle 86 gives these periodic impulses a lateral component which tends to cause the tool holder to vibrate with the pilot stem in a lateral direction, somewhat like the vibration of a tuning fork. Thus the tool holder is subjected to vertical impulses and/or vibrations and to lateral impulses and/or vibrations, and the grinding wheel is subjected to variations in vertical pressure and variations in angular movement about the lower end of the pilot as a center, which permits the grind-

ing wheel to lift slightly from its working surface and disperse the cuttings.

The exact theory on which the action is based cannot be certainly determined, but it is positively known that the swaying action of the motor driver with the structure of the pilot, tool holder and shock absorbing springs as described results in a complete dispersion of the cuttings while the grinder is operating, and the grinder is capable of producing a substantially mirror-like valve surface without any grooves or other irregularities and without producing any noticeable wear on the grinding stone. All of this may be done at a very high speed, the high speed aiding the smooth action of the grinder and subjecting the grinder to high frequency vibration as well as increasing the speed at which the work may be done.

Assuming a rotary speed of 13,000 R. P. M., using a hexagonal driving knuckle, each corner of the grinding knuckle will produce one complete vertical oscillation or variation in pressure or lateral oscillation on the pilot because the impulse which is given to the tool holder by the corners of the hexagonal driving knuckle takes place between the flat portion of the driving knuckle and each corner. The frequency of vibration would, therefore, be six times 13,000, or in the range of 78,000 complete vibrations per minute.

It should also be pointed out that the grinder is preferably supplied with a rough or coarse stone and with a relatively fine finishing stone, in order to secure the best possible finish, but a mirror-like surface of extremely smooth and uniform characteristics can be produced on a valve seat with the present grinder, even by the use of a relatively coarse stone.

The mode of operation of the present apparatus and the method of reconstructing valve seats according to the present invention may be described as follows:

The grinding stone is first dressed to an accurate frusto-conical surface of predetermined angularity, determined by the angularity of the valve seat in question. The valve stem pilot is then fixedly secured in the valve stem guide by shoving the tapered portion of the pilot down into the guide until the pilot is fixed therein. The tool holder bearing the grinding stone is then slidably and rotatably mounted on the guide, and the motor driver is held above with its driving knuckle, having the non-circular end in the non-circular socket of the tool holder.

It is not necessary to exert any pressure on the motor driver, but, on the contrary, a very light pressure is desirable, such as that exerted by the weight of the motor itself. The motor may then be turned on and the grinding stone and tool holder rotated at a high speed of approximately 13,000 R. P. M., while the handle of the motor is oscillated back and forth through a small arc of from fifteen to thirty degrees, more or less, depending upon the range of motion permitted by the clearance between the non-circular socket and the non-circular end of the drive shaft.

The high frequency vibration results in the dispersion of the cuttings and produces a mirror-like seat without any substantial effect on the grinding stone.

The method of grinding valve seats may be described as rotating a grinding stone in full contact with a valve seat, while subjecting the grinding stone to periodic vibrations, varying the

pressure and/or area of contact of the stone by angular oscillations of the stone in such manner as to constantly disperse the cuttings, and prevent clogging or loading of the stone.

It will thus be observed that I have invented an improved valve seat grinder, the structure of which is considerably simplified over the devices of the prior art, inasmuch as it does not require any complicated driving mechanism for both rotating and revolving the stone, and yet the device effects a dispersion of the cuttings, constant cleaning of the stone, and produces a mirror-like finish on the valve seat, which could not be done with the full contact stones of the prior art.

The spring action of the resiliently mounted drive shaft prevents shocks to the stone by means of the mass of the motor and the periodic impulses transmitted to the tool holder and stone by means of the resiliently mounted drive shaft produces a vibratory action of the stone, which slightly lifts the stone from its seat periodically as the grinding progresses and permits the cuttings to be thrown off centrifugally, this action being also guided by the air currents caused by the rotating stone.

The present grinding apparatus is so simple that it may be manufactured at a much lower cost than the complicated devices of the prior art, particularly the eccentric type of grinders, and this grinder may be manufactured at a cost which is within the means of a vast number of purchasers.

The present angular attachment provides a means whereby any ordinary driving motor may be provided with a drive shaft removably secured thereto and having proper characteristics for use in practising the present method. The angular attachment may, of course, also be used with the regular driver for access to the valve seats which are disposed in relatively inaccessible positions under the dash, and the scope of usefulness of the grinder is greatly extended by means of this angular attachment.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a valve seat grinding apparatus, the combination of a pilot stem adapted to be fixedly secured in centered position in a valve stem guide, with a grinding wheel holder slidably and rotatably mounted on said pilot, a motor driver adapted to rotate said grinding wheel holder, a grinding wheel and an angular attachment providing an operative connection between said motor driver and said grinding wheel holder whereby said grinding wheel holder may be rotated in an upright position, with the motor driver disposed at an angle, said angular attachment having a drive shaft resiliently mounted in said angular attachment for reciprocating movement against the compression of a spring resiliently to support the weight of the motor.

2. In an angular attachment for grinding machine drivers, a housing having means for attaching said housing to the housing of a motor driver, a driven shaft fixedly mounted in said attachment housing and having a socket for receiving

the end of the drive shaft, a second driven shaft rotatably and reciprocably mounted in said angular attachment, and resilient means for urging said driven shaft outward with respect to 5 said angular attachment whereby said angular attachment is resiliently supported when its weight rests upon said driven shaft.

3. In an angular attachment for grinding machine drivers, a housing having means for attaching said housing to the housing of a motor driver, a driven shaft fixedly mounted in said attachment housing and having a socket for receiving the end of the driver shaft, a second driven shaft rotatably and reciprocably mounted 10 in said angular attachment, resilient means for urging said driven shaft outward with respect to said angular attachment whereby said angular attachment is resiliently supported when its weight rests upon said driven shaft, and operative 15 mechanical connections between said second driven shaft comprising a pair of pinions carried by said shafts intermeshing each other and having their teeth spaced from the bases of the tooth spaces to permit axial movement of 20 said second driven shaft.

4. A driving device for valve seat grinders comprising a motor driver having a projecting drive shaft with a hub surrounding said drive shaft, an attachment comprising a tubular housing adapted 25 to be clamped to said hub, said tubular housing having a driven shaft with a socket for receiving said drive shaft, and a second shaft disposed in said tubular housing at an angle to the first-mentioned driven shaft whereby the 30 motor may be disposed at an angle to the second shaft to prevent interference with the dash of a motor vehicle in grinding the valve seats adjacent thereto, said second shaft having an anti-friction bearing slidably mounted in said 35 tubular housing, and resilient means for urging 40 said second shaft outward with respect to said tubular housing.

5. An angular attachment for motor drivers comprising a tubular housing having two cylindrical parts, the axes of which are at an angle to each other, a shaft mounted in each of said cylindrical parts for rotary movement, one of 45 said shafts being mounted also for reciprocatory movement along its axis, pinions carried by the 50 adjacent ends of said shafts, said pinions intermeshing and having sufficient clearance between the teeth of one pinion and the base of the tooth spaces of the other pinion to permit reciprocatory movement of one of said shafts.

6. An angular attachment for motor drivers comprising a tubular housing having two cylindrical parts, the axes of which are at an angle to each other, a shaft mounted in each of said cylindrical parts for rotary movement, one of 5 said shafts being mounted also for reciprocatory movement along its axis, pinions carried by the adjacent ends of said shafts, said pinions intermeshing and having sufficient clearance between the teeth of one pinion and the base of the tooth 10 spaces of the other pinion to permit reciprocatory movement of one of said shafts, an anti-friction bearing for said reciprocably mounted shaft, and resilient means interposed between 15 said tubular housing and said anti-friction bearing for urging said reciprocably mounted shaft outward with respect to said housing.

7. An angular attachment for motor drivers comprising a tubular housing having two cylindrical parts, the axes of which are at an angle to each other, a shaft mounted in each of said cylindrical parts for rotary movement, one of 20 said shafts being mounted also for reciprocatory movement along its axis, pinions carried by the adjacent ends of said shafts, said pinions intermeshing and having sufficient clearance between the teeth of one pinion and the base of the tooth 25 spaces of the other pinion to permit reciprocatory movement of one of said shafts, an anti-friction bearing for said reciprocably mounted shaft, and resilient means interposed between 30 said tubular housing and said anti-friction bearing for urging said reciprocably mounted shaft outward with respect to said housing, said resilient means comprising a tempered steel washer having a 35 plurality of resilient metal tongues bent out of the body of said washer.

8. In a valve seat grinding apparatus, the combination of a pilot stem adapted to be fixedly secured in centered position in a valve stem guide 40 with a grinding wheel holder slidably and rotatably mounted on said pilot, a grinding wheel carried by said holder, a motor driver adapted to drive said grinding wheel holder, said motor driver having a drive shaft, and an auxiliary 45 drive shaft disposed at an angle to said first-mentioned drive shaft, resilient means interposed between said auxiliary shaft and said tool holder to absorb shocks, and a non-circular connecting device between said wheel holder and said auxiliary shaft adapted to place said holder and wheel 50 in a state of vibration on said pilot stem during its rotation.

FRANS O. ALBERTSON.
